CARTON

Norman H. Moore, Palo Alto, Calif., assignor to Fibre-board Paper Products Corporation, San Francisco, Calif., a corporation of Delaware

Filed Aug. 13, 1962, Ser. No. 216,504

2 Claims. (Cl. 229—51)

This invention relates to a carton and more particularly relates to a carton blank which may be formed into a closed carton adapted to be opened and thereafter closed to prevent contamination and leakage of the contents thereof.

Leakage problems are particularly apparent with respect to the packaging of ice cream and like products. The primary problem is one of providing a carton which is leak-proof when such products are maintained in a liquid state therein. For example, during the packaging of ice cream a first end of the carton is closed while an open second end thereof is arranged to receive unfrozen ice cream. The second end is thereafter also closed and the ice cream is then frozen. The problems presented due to leakage of the non-frozen ice cream from the carton are apparent. Furthermore, it is desirable to provide the consumer with a leak-proof carton for such products which may be expeditiously opened and reclosed to maintain the contained product in an uncontaminated condition.

Conventional ice cream cartons generally comprise end portions employing lock-tab arrangements or the like which are highly prone to leakage. Leakage problems are inherent therewith primarily due to the inefficient constructions and arrangements of the end portions thereof. Also, such cartons are generally cumbersome to open and cannot always be reclosed to prevent contamination of the product which is contained therein.

The present invention has overcome many of the above described difficulties by providing a carton blank which may be expeditiously formed into a reclosable carton which is highly resistant to leakage. The blank comprises five consecutive hingedly connected panels each having a pair of symmetrically arranged flaps hingedly connected thereto. The panels and flaps are uniquely constructed and arranged so that a flap which is hingedly connected to the top panel thereof may be arranged to nestle in substantial seating engagement with mating edge portions formed on flaps of a front inner panel and rear panel to thereby aid in the prevention of leakage through the end portions of the erected carton. Further novel concepts of this invention provide an erected carton arrangement wherein the flaps formed on the top panel overlie flaps hingedly connected to the bottom panel, the flaps formed on the rear panel are attached to the flaps of the top and bottom panels, the flaps of a front outer panel are secured to the flaps of the front inner panel and the flaps of the top panel and the flaps of the front inner panel are secured to the flaps of the bottom panel. As will be hereinafter more fully understood, a tear strip is formed in the outer front panel and flaps thereof to cooperate with the above described integrated constructions and arrangements to provide a reclosable carton comprising a body and cover assembly, capable of efficiently preventing leakage and contamination of the carton contents.

2

An object of this invention is to provide a carton blank of simple construction which may be expeditiously and economically manufactured and readily formed into a reclosable carton.

5 Another object of this invention is to provide a carton blank which is constructed and arranged to permit the expeditious forming of a reclosable and leak-proof carton.

A further object of this invention is to provide a leak-proof carton which may be expeditiously opened and thereafter closed to prevent contamination of the carton contents.

10 A still further object of this invention is to provide a reclosable carton having integrated panel flaps forming end closures arranged to prevent leakage thereby when the carton is filled with a liquid or the like.

15 Other and more specific objects of this invention will become apparent from the following description taken in connection with the accompanying drawings wherein:

20 FIG. 1 is a plan view of the inside surface portions of a carton blank, constructed and arranged in conformance with novel concepts of this invention.

25 FIG. 2 is a perspective view disclosing a closed carton having a substantially rectangular cross-section formed from the blank shown in FIG. 1.

FIG. 3 is a perspective view disclosing the carton of FIG. 2 in opened condition; and

30 FIG. 4 is a perspective view of the carton of FIG. 2 as it would appear in its substantially formed condition.

35 The carton blank of FIG. 1, disclosing the inner surface portions of the subsequently formed carton, is shown as symmetrically arranged on a longitudinal axis X—X. The length dimensions of various portions of the blank should be herein understood to be taken in a direction along this axis while the width dimensions of such portions should be understood to be taken laterally thereof. It should be further understood that the sides of the blank, divided by axis X—X, are substantially identical and therefore, the discussion herein will be primarily directed to only one side.

40 Score lines 10 are formed in parallel relationship on the blank relative to axis X—X, and define first to fifth consecutive hingedly connected panels 11—15 having first to fifth pairs of flaps 11a—15a, respectively, hingedly attached at the score lines. As will be hereinafter more fully understood, the blank may be expeditiously formed into the closed carton arrangement of FIG. 2 with the first or outer-front panel 11 arranged in overlying and attached relationship to the fifth or inner-front panel 15 and the remaining panel flaps integrated therewith in a

45 novel manner to form leakproof end closures. As more clearly shown in the substantially formed carton of FIG. 4, flap 12a of the second or top panel 12 overlies upstanding flap 14a of the fourth or bottom panel 14 and flaps 11a, 13a and 15a are arranged to be placed in overlying

50 relationship with and selectively attached to flaps 12a and 14a. Thus, removal of a tear strip 16, formed in panel 11 and flaps 11a thereof, permits a raising of the formed cover assembly to the open position shown in FIG. 3. The upstanding front, rear and two end portions of the

55 formed carton thereafter provide four coextensive, leak-proof wall portions which form a body assembly to efficiently contain the carton contents.

60 Reference is now to the more specific constructions and arrangements of the carton blank shown in FIG. 1.

65 The blank may comprise paperboard or any suitable

carton material. The first or outer-front panel 11 is hingedly connected to the second or top panel 12 at score line 21. Tear strip 16 is formed by two substantially parallel and laterally extending knife cuts which may be formed in one or both sides of panel 11 and first flaps 11a. Notches 22 are formed in flap 11a to facilitate removal of the tear strip, as will be hereinafter more fully understood. The tear strip is arranged to divide the panel and flaps thereof into a first portion adjacent panel 12 and a second portion. Slits 33 are formed in this panel, coincident with score lines 10, and terminate at the tear strip. An L-shaped adhesive or glue pattern 24 is formed by standard techniques on first flap portions of the first portions of the first panel and first flap adjacent to the second flap and lateral edge of the first flap.

Panel 12 is hingedly connected to the third or back panel 13 at score line 26. The second flap 12a thereof is constructed to have a laterally extending width substantially equal to the length of the above-described first portion of panel 11 and flaps 11a. Flap 12a is disconnected from flap 13a at slit 27. Intersecting edge portions 28 of flaps 12a form a substantial V-shaped configuration, one of the edge portions thereof opposing the first flap and arranged to extend from and forming an angle of approximately 60° relative to score line 10.

Panel 13 is hingedly connected to the fourth or bottom panel 14 at a score line 29, the score line terminating in a slit 30 arranged to disconnect third flap 13a and fourth flap 14a. Flap 13a has a disconnectable tab 13b formed thereon, bounded by slit 31 and perforated tear line 32, preferably arranged to extend at an angle of approximately 45° relative to score line 10. The length of the tab substantially equals the lateral width of flap 12. An L-shaped adhesive pattern 33 is formed on the tab and a rectangularly shaped adhesive pattern 34 is formed on the substantial remaining surface portions of flap 13a.

Panel 14 is hingedly connected to fifth or outer-front panel 15 at score line 35, the score line laterally terminating a slit 36 which disconnects fourth flap 14a from fifth flap 15a. Flap 14a preferably has a width substantially equal to the length of panel 13 and further has a length substantially equal to the width thereof.

Flap 15a has a V-shaped cutout portion arranged adjacent to an outer edge of panel 15 and formed by intersecting edge portions 37 and 38 constructed and arranged to substantially conform to the V-shaped configuration 28 of flap 12a for purposes hereinafter more fully understood. A notched-out portion 39 is arranged to cooperate with the tear strip arrangement of panel 11 in the erected carton to facilitate an opening thereof. A substantially rectangularly shaped adhesive pattern 40 is formed on flap 15a and functions with the other hereinbefore described adhesive patterns to efficiently seal the end portions of the erected carton. The added widths of flap 13a and 15a are preferably constructed to be no greater than the length of flap 14a.

FIG. 2 discloses a closed carton formed from the carton blank of FIG. 1. The five panels are initially suitably folded to position panel 11 in overlying relationship with respect to panel 15. A standard adhesive may then be utilized to attach the above-described second portion of panel 11 and flaps 12 to matching underlying surface portions of panel 15 and flaps 15a to form a conventional manufacturer's glue joint, as shown at 41 in FIG. 4. The front panels and flaps are thus secured together, below the detachable tear strip 16 to permit shipping of the folded carton sub-assembly.

The folded carton sub-assembly may be thereafter formed into the carton shown in FIG. 2 in the following manner. A first end portion of the carton is first closed by placing one of the flaps 12a in overlying relationship with respect to one of the flaps 14a, as more clearly shown in FIG. 4. Flap 11a and 15a, connected together as above described, are then folded along with flap 13a to overlie flaps 12a and 14a in the manner shown. Flap

15a may have a slit 42 formed therein to facilitate folding. Heat is thereafter suitably applied to the adhesive patterns to bond mating surface portions of the carton together. The pre-applied adhesive is preferably of the resinous, hot-melt and heat sealing type. The carton may then be arranged on a conveyor or the like with the open end portion thereof being positioned to receive a liquid constituent, such as unfrozen ice cream. The open end portion of the carton is thereafter closed in substantially the same manner as above described.

Expeditious removal of tear strip 16 which is arranged below the intersecting edge portions 28, 37 and 38 is aided due to the cooperating arrangement of notches 22 and notched-out portions 39. As shown, lateral portions of tear strip 16 are arranged to extend over the notched-out portions. Removal of the tear strip thus permits a raising of the cover assembly comprising the above-described first portion of panel 11 and flaps 11a, cover panel 12, flaps 12a and tab 13b of flap 13a to the position shown in FIG. 3. Tabs 13b may be expeditiously removed due to the above-described arrangement of slit 31 and perforated tear line 32. A body assembly constituting four coextensive wall portions is thus provided for efficient retention of the carton contents.

It should be noted that slit 31 is arranged so that the upwardly facing edge formed thereby on flap 13a may be thereafter maintained in substantial abutting relationship with the downwardly facing edge of flap 12a to minimize the possibility of leakage thereby. Also, flaps 13a do not overlap with either flaps 11a or 15a and edge portions 28 of flaps 12 are arranged to abut and be seated in edge portions 37 and 38 of flaps 15a to further increase the sealing efficiency of the carton. Thus a reclosable carton is provided which may be reused without affecting sealing efficiency.

I claim:

1. A carton blank symmetrically arranged on a longitudinal axis and having a length as taken along said axis and width as taken laterally thereof, parallel score lines formed on said blank in parallel relationship to said axis defining first to fifth consecutive hingedly connected panels having first to fifth pairs of flaps hingedly connected at said score lines thereto, respectively, said flaps having widths arranged to extend laterally relative to said axis, the first of said panels and said first flaps thereof having a laterally extending tear strip formed therein for division thereof into a first portion adjacent the second of said panels and a second portion, slits formed in said second portion and arranged coincident with said score lines and terminating at said tear strip, said second flaps having laterally extending widths substantially equal to the length of the first portion of said first panel and first flaps and having edge portions forming a substantially V-shaped configuration, one of said edge portions opposing said first flaps and arranged to extend from and forming an angle of approximately 60° relative to the score line which connects the second flaps to said second panel, the third flaps arranged in disconnected relationship relative to the second and fourth flaps and having a disconnectable tab formed thereon having a length substantially equal to the lateral width of said second flap, said tab being bounded by a perforated tear line extending from and at an angle of approximately 45° relative to the score line which connects the third flaps to the third panel and a laterally extending slit, said fourth flaps arranged in disconnected relationship relative to said fifth flaps and having lateral widths substantially equal to the length of said third panel and further having lengths substantially equal to the width thereof, said fifth flaps having V-shaped cutout portions arranged adjacent an outer edge of said fifth panel and formed by edge portions constructed and arranged to substantially conform to the V-shaped configuration of the edge portions of said second flaps, said third and fifth flaps having substantially equal laterally extending

widths, the total of which is no greater than the length of said fourth flap.

2. The invention of claim 1 further comprising L-shaped adhesive patterns formed on the first flap portions of the first portions of said first panel and first flaps adjacent to said second flaps and outer lateral edges of said first flaps, adhesive patterns formed on said discon- 5 nectable tabs of said third flaps and rectangularly-shaped glue patterns formed on the remaining portions of said third flaps and substantially rectangularly-shaped ad- 10hesive patterns formed on said fifth flaps.
